UNITED STATES PATENT OFFICE

HENRY NENDORF AND ARTHUR W. COLE, OF KALAMAZOO, MICHIGAN, ASSIGNORS TO
REX PAPER COMPANY, OF KALAMAZOO, MICHIGAN

PAPER-COATING MACHINE

Application filed November 10, 1928. Serial No. 318,356.

The main object of this invention is to provide an improved paper coating machine adapted for applying a coating of different colors to one side of a web of paper with the edges of the coating meeting.

A further object is to provide a machine of this character in which the line of division between the colors is distinct, that is, the colors do not overlap.

10 Objects pertaining to details and economies of our invention will definitely appear from the description to follow. The invention is defined in the claims.

A structure which embodies the features 15 of our invention is clearly illustrated in the accompanying drawing in which:

Fig. 1 is a fragmentary perspective view 20 of our improved coating machine. Parts which are not necessary to show the relation 25 of our improvements are omitted, certain parts are shown in full lines and others are shown in dotted lines for convenience in illustration.

Fig. 2 is a fragmentary view partially in 25 vertical transverse section on line 2—2 of Fig. 3.

Fig. 3 is a fragmentary view partially in 30 longitudinal section.

We have illustrated only the front end of 35 a coating machine and have not attempted to illustrate in detail or describe the driving connections as these will be understood by those skilled in the art.

1 represents the web of paper to be coated 40 and 2 the roll of paper. At the front end of the machine we mount a coating pan 3 having spaced partitions 4 therein providing a pair of coating receptacles or compartments 5 and a narrow intermediate compartment 6. This intermediate compartment has a drain 45 hole 7 at the bottom thereof.

The coating feed rollers 8 are mounted on 50 a shaft 9 which extends above the intermediate compartment 6. On this shaft we mount a disk 10 to depend into the intermediate compartment. Any of the coating material traveling along the shaft 9 from the coating rollers is caught by this disk 10 55 and drops therefrom into the compartment

6, from which it is discharged through the drain opening 7.

The rotary coating brush 11 is mounted 60 in coating relation to the coating feed rollers and delivers the coating material to the paper as it passes over the paper supporting drum 12. The periphery of the disk 10 projects beyond the peripheries of the rollers 8 so that the periphery of the disk embeds itself into the fibers of the brush.

The scrubber brushes 13 are arranged to 65 act upon the paper as it passes over the drum, these brushes being arranged in pairs end to end and there being a space between their inner ends as shown in Fig. 1. These brushes are carried by reciprocating bars 14. The means for reciprocating the bars is not illustrated and described in detail.

At the rear of the drum 12 is a conveyor 70 apron 15 to which the paper passes from the drum 12. Finishing brushes are arranged to act on the paper while it is supported by the apron, one of these brushes being shown at 16.

We have illustrated and described our improvements in a form in which we have embodied the same in a coating machine of the type illustrated in the patent to Thorne, No. 1,675,066, issued June 26, 1928. We have not attempted to illustrate or describe certain 80 modifications or adaptations which might be desirable to adapt the same to certain other types of coating machines as we believe the disclosure made will enable those skilled in the art to embody or adapt our improvements 85 as may be desired.

Having thus described our invention, what we claim as new and desire to secure by Letters Patent, is:

1. The combination in a paper coating machine, of a coating pan having spaced partitions providing coating compartments and a narrow intermediate compartment, said intermediate compartment having a drain opening in the bottom thereof, feed rollers 90 disposed in operative relation to said coating compartments, a shaft for said feed rollers, a rotary coating brush operatively associated with both of said feed rollers, and a disk 95 mounted on said feed roller shaft to depend 100

into said intermediate compartment and projecting beyond the peripheries of the feed roller into the fibers of said coating brush.

2. The combination in a paper coating machine, of a coating pan having spaced partitions providing coating compartments and a narrow intermediate compartment, said intermediate compartment having a drain opening in the bottom thereof, feed rollers disposed in operative relation to said coating compartments, a shaft for said feed rollers, a rotary coating brush operatively associated with said feed rollers, and a disk mounted on said feed roller shaft to depend into said intermediate compartment.

3. The combination in a paper coating machine of spaced coating receptacles, feed rollers operatively associated with said coating receptacles, a shaft for said feed rollers, a rotary coating brush operatively associated with both of said feed rollers, and a disk mounted on said feed roller shaft between and in spaced relation to the adjacent ends of said feed rollers and projecting beyond the peripheries thereof into the fibers of said coating brush.

4. The combination in a paper coating machine, of spaced coating receptacles, feed rollers operatively associated with said coating receptacles, a shaft for said feed rollers, a rotary coating brush operatively associated with said feed rollers, and a disk mounted on said feed roller shaft between and in spaced relation to the adjacent ends of said feed rollers.

5. The combination in a paper coating machine, of feed rollers arranged in alinement and in spaced relation, a disk disposed between said feed rollers and rotatable therewith, and a rotary brush operatively associated with said feed rollers, said disk projecting beyond the peripheries of the feed rollers into the fibers of said brush.

6. The combination in a paper coating machine, of feed rollers arranged in alinement and in spaced relation, a disk disposed between said feed rollers and rotatable therewith, and a rotary brush operatively associated with said feed rollers.

50 7. The combination in a paper coating machine, of a coating pan having spaced partitions providing coating compartments and an intermediate compartment, feed rollers disposed in operative relation to said coating compartment, a shaft for said feed rollers extending across said intermediate compartment, and a disk mounted on said shaft to depend into said intermediate compartment.

In witness whereof we have hereunto set
60 our hands.

HENRY NENDORF.
ARTHUR W. COLE.
